HIDE FINISHING APPARATUS

William B. Quinn, Philadelphia, Pa.

Application July 6, 1935, Serial No. 30,108

6 Claims. (Cl. 51—72)

This invention relates to apparatus for finishing hides and is concerned primarily with finishing machines which include, as a finishing element, an abrading wheel.

At the present time, operators of the now known types of finishing machines are experiencing considerable difficulty in maintaining the hides in proper engagement with the abrading wheels, this condition being largely due to the necessity for maintaining an appreciable degree of tension on the skins and at the same time maintaining them spread out flatly on the abrading surface.

With the foregoing in mind, this invention has in view as an important object the provision of hide finishing apparatus which includes an abrading wheel with which are associated instrumentalities for maintaining a hide in operative engagement with the abrading wheel under any desired degree of pressure.

Another end in view is the provision of instrumentalities of the character above noted which include, as an essential element, an endless belt having a surface positioned in close proximity to the abrading wheel and which surface is movable in the same direction as the corresponding surface of the abrading element.

A somewhat more detailed objective is the provision of an endless belt of the character above noted which is pivotally mounted at one end and which is movable on said pivot to vary the pressure which is applied to hides positioned between the said belt and the abrading wheel.

Yet another object in view is to provide, in a hide finishing machine of the type above noted, an abrading wheel and a pressure member in the form of an endless belt, together with driving mechanism therefore which is effective to drive the wheel and the belt at the same surface speeds. In carrying out this idea in a practical embodiment, I propose to drive both the belt and the wheel from a common drive shaft so that the inter-relation of their respective speeds is at all times assured.

A further object of the invention is to provide, in a hide finishing machine including an abrading wheel, pressure instrumentalities which are adjustable to accommodate the particular requirements of any individual operator and which instrumentalities are effective to apply varying pressures on the hides being finished.

Various other more detailed objects and advantages are associated with the carrying out of the above noted objectives in a practical working apparatus.

The invention therefore comprises a supporting table on which is mounted an abrading wheel and pressure instrumentalities for applying pressure to hides as they are affected by the abrading wheel, which instrumentalities consist of an endless belt which is carried by a frame which is pivotally mounted and which frame is adjustable. The apparatus also includes means for applying downward pressure to the frame carrying the belt so that a corresponding pressure may be implied to the hides. Other detailed parts of the apparatus include the driving connections, tensioning means for the endless belt, and the yielding means for normally maintaining the belt spaced from the wheel.

For a full and more complete understanding of the invention, reference may be had to the following description and accompanying drawing wherein:

Figure 1 is a plan view of a hide finishing machine made in accordance with the percepts of this invention, and

Figure 2 is a view in side elevation of the machine shown in Figure 1.

Referring now to the drawing wherein like reference characters denote corresponding parts, the apparatus constituting the machine of this invention is shown as mounted on a supporting table, referred to generally by the reference character A. This table includes upstanding legs 10 which may be secured to a floor or similar surface, as indicated at 11, and at their upper extremities the legs 10 carry a table top designated 12. A counter-shaft is shown at 13 as being rotatably mounted on the under surface of the table top 12 and this counter-shaft 13 is driven from a suitable power source, such as the electric motor indicated at 14, which is connected to the counter-shaft 13 by a driving belt 15. Obviously, the counter-shaft 13 could be driven from any power source desired.

An abrading wheel is shown at 16 and may take the form of any of the well-known wheels of this character. This wheel 16 is shown as being non-rotatably mounted on a shaft 17 that finds bearing in brackets 18 mounted on the under surface of the table top 12. The latter is provided with a cut-out portion to receive the wheel 16, which wheel is shown in dotted lines in Figure 1.

A pulley 19 is drivably carried by the shaft 17 and from this pulley 19 extends a driving belt 20 which is crossed as shown in Figure 2, and which belt extends to a pulley mounted on the counter-shaft 13. It is evident that upon movement of

the belt 15 in the direction indicated by the arrows on Figure 2, the counter-shaft 13 will be driven in a clockwise direction which, due to the crossing of the belt 20, will drive the abrading wheel 16 in a counter-clockwise direction as shown by the arrow on the wheel 16.

Upstanding from the table top 12 is a pair of spaced legs 21 which may be secured to the table top 12 in any preferred manner, such as by the pedestals shown at 22 which may be bolted to the table top 12. A pair of spaced side bars 23 extend forwardly of the table from the upper extremities of the legs 21. As shown in Figure 2, diagonal bars 24 serve to brace the connection 15 between the legs 21 and bars 23 so as to insure the rigid mounting of the latter. In this connection, it is notable that this invention contemplates the adjustment of the angle between the bars 23 and legs 21. This adjustment may be effected by varying the position of the fastening members shown at 25. Bracing members 26 also may be included in the upper framework and these members are connected at one end to the table top as shown at 27 and at their upper 25 ends to the upper extremities of the legs 21.

A shaft 28 has bearing at the upper extremities of the legs 21 and this shaft 28 is provided with a gear 29 and a pair of pulleys 30, all of which are drivably carried by the shaft 28. The 30 counter-shaft 13 has non-rotatably mounted thereon, a pinion 31 and a chain 32 extends from the pinion 31 and gear 29 to provide the driving connection between the counter-shaft 13 and the shaft 28.

35 At the forward extremities of the side bars 23, a shaft 33 extends thereacross, and is retained in operative position in any preferred manner, as by the nuts indicated at 34. This shaft 33 carries a pair of pulleys 35, corresponding to the 40 pulleys 30 on the shaft 28, and a pair of driving belts 36 extend from the pulleys 30 and 35 to drivably connect the shaft 33 with the shaft 28. A roller 37 is carried by the shaft 33 for a purpose to be hereinafter described.

45 Pivottally attached to the shaft 33 is a framework comprising side bars 38 and crossbars 39, 40, 41 and 42. The side bars 38 may be angle bars and their ends are cut away as shown at 43 to accommodate the roller 37. These ends are 50 of a curved construction as shown at 44 in Figure 2 and the extremities of these curved parts 43 are provided with openings which receive the shaft 33. At the end opposite to the shaft 33, the side bars 38 are of a similarly cut away and 55 curved construction and carry a shaft 45 which in turn carries a roller 46.

An endless belt which may be made from any suitable fabric is shown at 47 as extending from and about the rollers 37 and 46, and this belt 47 is driven incident to rotation of the shaft 33. Upon reference to Figure 2, it will be noted that as the belt 47 is driven from the counter-shaft 13 by the driving connections, including chain 32, shaft 28, belts 36 and shaft 33, the under surface 60 of the belt 47 will be driven in a direction corresponding to that in which the upper surface of the abrading wheel 16 is driven. Means for maintaining the proper tension on the belt 47 between the rollers 37 and 46 so as to take up 65 any slack in the belt, is shown in the form of a roller 48 which is carried between arms 49 that are in turn affixed to the crossbar 39 as indicated at 50.

A pair of leaf springs is shown at 51 as normally urging the roller 48 downwardly so as to

take up slack in the belt 47. Extending across the top of the side bars 23 is a yoke member 52, and a spring 53 is connected at one end to the top of the yoke member 52 and at its other extremity to the crossbar 41. This spring normally 5 maintains the framework carrying the belt 47 in an upraised position in which it is spaced from the abrading wheel 16.

Means for urging the framework and belt 47 downwardly against the influence of the spring 10 53 is shown in the form of a pair of arms 54 which are interlocked with the crossbars 40, 41 and 42, as shown in Figure 1. Connected to the free ends of the arms 54, as indicated at 55, is a pair of cables 56 which extend downwardly 15 through openings in the table top 12 about a pair of pulleys 57 and along the under side of the table top 12 to a point where they pass about another pair of pulleys 58 at the forward end of the table. The ends of these cables 56 are anchored 20 to a treadle designated 59 which may be pivotally mounted as shown at 60 on the front legs 10. It is evident that upon the operator urging the treadle 59 downwardly by the use of his foot, the cables 56 will be pulled to cause the 25 corresponding downward movement of the frame and the belt 47.

Intermediate the upper and lower surfaces of the belt 47, there is shown a backing member 61 which is provided with an arcuate surface 62 30 that corresponds in curvature to the upper surface of the abrading wheel 16. This backing member 61 may be pivotally carried by arms 63, which depend downwardly from the crossbar 40. This backing member 61 serves to insure a solid 35 backing for the application of pressure to skins being finished.

In the operation of the above described apparatus, the motor 14 is started whereupon the abrading wheel 16 and belt 47 will be driven in 40 the direction indicated by the arrows. Without the application of pressure to the treadle 59, the belt 47 is spaced from the abrading wheel. A hide, such as a sheep skin, which is to be finished may now be inserted between the abrading wheel 45 16 and belt 47, whereupon the operator steps on the treadle 59 to apply a desired amount of pressure to the hide. The latter is firmly held by both hands of the operator so that it may be moved in all directions across the abrading wheel 50 to have the proper finish applied thereto. Upon release of the foot of the operator from the treadle 59, the spring 53 returns the belt 47 to its 55 upraised position.

While a preferred specific embodiment of the 55 invention is herein set forth, it is to be understood that I am not to be limited to the exact constructions illustrated and described because various modifications of these details may be provided in putting the invention into practice with- 60 in the purview of the appended claims.

I claim:

1. Hide finishing apparatus of the character described comprising an abrading wheel, a pair of spaced rollers disposed on opposite sides of the 65 abrading wheel, an endless belt spaced from the abrading wheel and carried by the rollers and movable toward and from the abrading wheel about one of the rollers as a pivot, and means for driving the said abrading wheel and endless belt. 70

2. Hide finishing apparatus of the character described comprising a finishing wheel, a pair of spaced rollers, an endless belt carried by the rollers in operative relation with respect to the finishing wheel, and a means common to the wheel and 75

belt for driving both with the same surface speeds in the same direction.

3. Hide finishing apparatus comprising a supporting member, a finishing wheel operatively mounted on the supporting member and a framework pivotally mounted on the supporting member, said framework including a pair of spaced rollers, one of which is co-axial with respect to the pivotal mounting of the framework, an endless belt carried by the rollers, a backing member also carried by the framework, said backing member being positioned interiorly of the endless belt, and means to urge the framework towards the abrading wheel to apply pressure to a hide in engagement with the abrading wheel.
4. Hide finishing apparatus comprising a supporting table, an abrading wheel operatively carried by the supporting table, a counter-shaft carried by the table, driving connections between the counter-shaft and the abrading wheel, a framework on the table including a pair of arms extending above the abrading wheel, a second framework pivotally carried by the said arms, rollers in said second mentioned framework, an endless belt extending about said rollers, driving connections between the shaft on the table and one of said rollers, means for yieldably maintaining the belt spaced from the abrading wheel, means for urging the belt toward the abrading wheel, said means including a treadle operatively mounted at one end on the table, and operative connections between the treadle and the second mentioned framework.
5. Hide finishing apparatus comprising a supporting table, an abrading wheel operatively carried by the supporting table, a counter-shaft carried by the table, driving connections between the counter-shaft and the abrading wheel, a framework on the table including a pair of arms extending above the abrading wheel, a second framework pivotally carried by the said arms, rollers in said second mentioned framework, an endless belt extending about said rollers, driving connections between the shaft on the table and one of said rollers, means for yieldably maintaining the belt spaced from the abrading wheel, means for urging the belt toward the abrading wheel, said means including a treadle operatively mounted at one end on the table, and operative connections between the treadle and the second mentioned framework.
6. Hide finishing apparatus including an abrading wheel, a pair of spaced rollers disposed on opposite sides of the abrading wheel, an endless belt spaced from the abrading wheel and carried by the rollers, said belt being movable toward and from the abrading wheel, and a backing member for said belt, said backing member having an arcuate portion complementary to the peripheral surface of the abrading wheel for moving a portion of said belt toward said wheel.

5. Hide finishing apparatus comprising a supporting table, an abrading wheel operatively carried by the supporting table, a counter-shaft carried by the table, driving connections between the counter-shaft and the abrading wheel, a framework on the table including a pair of arms extending above the abrading wheel, a second framework pivotally carried by the said arms, rollers in said second mentioned framework, an endless belt extending about said rollers, driving connections between the shaft on the table and one of said rollers, means for yieldably maintaining the belt spaced from the abrading wheel, means for urging the belt toward the abrading wheel, said means including a treadle operatively mounted at one end on the table, and operative connections between the treadle and the second mentioned framework.

6. Hide finishing apparatus including an abrading wheel, a pair of spaced rollers disposed on opposite sides of the abrading wheel, an endless belt spaced from the abrading wheel and carried by the rollers, said belt being movable toward and from the abrading wheel, and a backing member for said belt, said backing member having an arcuate portion complementary to the peripheral surface of the abrading wheel for moving a portion of said belt toward said wheel.

WILLIAM B. QUINN. 30
